COMBINED STARTING AND SAFETY DEVICE.

1,174,352.

Specification of Letters Patent.

Patented Mar. 7, 1916.

Application filed January 3, 1914. Serial No. 810,145.

To all whom it may concern:

Be it known that I, GEORGE C. RICHARDS, a citizen of the United States, residing at Berkeley, in the county of Alameda and State of California, have invented new and useful Improvements in Combined Starting and Safety Devices, of which the following is a specification.

This invention relates to a combined 10 starter and safety attachment.

The object of the present invention is to provide a simple, compact, easily operated connection, between the crank shaft of an internal combustion engine and an electrically driven starting motor, which will permit of the engine being started either by a hand-crank, of the usual construction, or by the electric motor.

Another object of the invention is to provide a safety connection which will prevent any back kick, either on the starting motor or hand-crank, if the engine should happen to back-fire.

Further objects will hereinafter appear. 25 The invention consists of the parts and the construction and combination of parts as hereinafter more fully described and claimed, having reference to the accompanying drawings, in which—

30 Figure 1 is a plan view showing the connection between the starting motor and the engine shaft. Fig. 2 is a section on line X—X, Fig. 1. Fig. 3 is a front view of the safety connection.

35 Referring to the drawings, A indicates the crank shaft of a gas engine or like machine; 2 an electrically driven starting motor; and 3 a driving pinion secured upon the shaft of the starting motor.

40 Suitably journaled in a standard 4 at one end and in a member 5 at the other end, hereinafter to be termed the "safety connection", is an extension shaft 6, upon which is secured a gear 7 which intermeshes with 45 the pinion 3. One end of the shaft is provided with a jaw clutch 8, which clutch 8 is adapted to be moved into driving connection with a similar clutch 9, formed or otherwise secured upon the end of the engine crank-shaft, and secured upon the opposite end of the shaft is another jaw clutch 10, of the usual construction, with which a hand crank 11 is adapted to be thrown into engagement.

55 Loosely mounted upon the shaft 6 is a

cam clutch 12 and a ratchet wheel 13. The clutch 12 and ratchet wheel 13 are formed integral with each other and are housed and journaled within the casing 5 and are enclosed therein by a plate 15. The clutch 12, 60 together with the ratchet wheel 13, is only adapted to revolve in the direction normally taken by the engine shaft, and suitable spring actuated pawl members 16, mounted in the lower part of the casing 5, are provided for the purpose of preventing the clutch, with the connected ratchet member, from revolving in the reverse direction if the engine should happen to back-fire.

Engageable with the clutch member 12 is 70 a pair of stud projections 17 and 18 which are secured on the end of the shaft. These are adapted to be thrown into engagement with the vertical shoulders 19 and 20 of the clutch member 12 to form an automatic releasing action, hereinafter to be described.

The shaft 6 is adapted to move longitudinally within the casing 5 and bearing 4 for the purpose of throwing the stud members 17 and 18 into engagement with the 80 shoulders on clutch 12, and also for the purpose of bringing the jaw clutches 8 and 9 into engagement with each other when it is desired to revolve the engine shaft A. This may be accomplished by two separate connections. The shaft, with connected parts, is normally actuated by a spring 20 which acts to hold the clutches 8 and 9 out of engagement with each other and similarly acts to throw the stud connections 17 and 18 out of engagement with shoulders 19 and 20 on the clutch 12.

One means for moving the shaft longitudinally is a rocker arm 21, which is pivotally mounted at 22 on a standard 23. One 95 end of the rocker arm is fork-shaped so as to straddle a collar 24 on shaft 6. The upper end of the lever is connected through a link 25 with a foot lever or like operating means, not here shown.

26 indicates a suitable form of electric switch having a pivotally mounted switch arm 27 and a contacting member 28. The upper end of the switch arm is engaged by a double flanged collar 29 so that any movement of the link 25 will cause the arm 27 to swing about its pivot into and out of connection with the contact member 28 for the purpose of closing a circuit through the starting motor 2.

100

105

110

The operation will be as follows: When it is desired to start the engine from the seat, it is only necessary to depress the foot lever in a direction which will cause the link 25 to rock the arm 21 in the direction of arrow *b*. This movement will be transmitted through the lower end of the lever and collar 24, and cause the shaft 6 to move in the direction of arrow *c*. The 5 first part of the movement transmitted to shaft 6 and also to the switch arm 27 is only sufficient to throw the switch arm 27 from the dotted line position indicated at 10 27' into connection with the contact member 28. This will close a circuit through wires 30, 31 and 32 which are connected with a suitable form of battery and start the motor revolving. Further movement of the shaft 6, after the motor has started and 15 when the shaft 6 is revolving, will bring the clutch 8 into engagement with the engine clutch 9 and movement will thus be transmitted to revolve the engine shaft in the direction indicated by arrow *a*. The 20 moment the engine starts, it can be seen that the clutches 8 and 9 will be thrown out of engagement as a few explosions within the cylinders will cause the engine to speed up beyond the speed of the shaft 6. The 25 inclined faces of the connected jaw clutches will thus slide away from each other and the shaft 6 will be moved back in the direction opposite to arrow *c* a sufficient distance to throw the clutches 8 and 9 out of engagement. This back movement is felt upon 30 the foot lever and the operator will then release this. Spring 20 will then act and move the gear 7, with connected shaft 6, back to the dotted line position indicated 35 at 7'. The backward movement of the shaft will correspondingly be transmitted through lever 21 and link 25 to move the switch lever 27 back to the dotted line position indicated at 27'. The circuit, between 40 the battery and starting motor 2, is thus broken and the motor is consequently cut out from the circuit or automatically 45 stopped.

If the engine should happen to back fire 50 the moment clutches 8 and 9 are thrown into engagement with each other, it can readily be seen that revolving motion, reverse to that indicated by arrow *a*, will immediately be transmitted to shaft 6, gears 55 7 and 3, and motor 2. This is, however, prevented, as the ratchet members 16 will immediately lock the ratchet wheel 13 and clutch 12 against reverse movement. The 60 stud members 17 and 18 being secured on the shaft and revolving in a direction opposite to that indicated by arrow *a* will then engage with the inclined surfaces 17' and 18' and will thus move the shaft 6 back in a direction opposite to that indicated by 65 arrow *c* and throw clutch 8 out of engage-

ment with clutch 9. The engine shaft will thus be free to revolve and any back kick on the starting motor and connected gears is thus prevented.

The engine may also be cranked by hand, 70 if desired, a hand crank 11 of the usual construction being provided for this purpose. In this instance it is only necessary to throw the crank 11 into engagement with clutch 10 and give the shaft 6 an inward 75 movement in the direction of arrow *c*, in opposition to the tension of spring 20. The inward movement of the shaft, caused by pressure of the hand crank 11, will move the shaft 6 in the direction of the arrow *c* 80 and bring clutch 8 into engagement with clutch 9 on the engine. It is then only necessary to turn the crank in the direction of arrow *a* in the usual manner to start the engine. Any back kick, if the engine 85 should happen to back fire, is obviated in this instance also as the stud members 17 and 18 will again ride up the inclined surfaces 17' and 18' of clutch 12 and pull the shaft 6, with connected clutch 8, out of engagement with the engine shaft. All danger of cranking the engine by hand is thus removed as shaft 6 can only revolve in a reverse direction a sufficient distance to cause the stud members 17 and 18 to ride 90 out of engagement with the clutch 12.

A device constructed as here shown is simple and compact in construction, may be operated as a self-starter or may be cranked by hand in the usual manner, if desired. 100

Any operation of the foot lever will automatically close the starting circuit through motor 2. The gears 7 and 3 are always intermeshing as pinion 3 is sufficiently long to permit the sliding movement desired. 105 Furthermore the provision of the safety connection including the clutch 12 and ratchet 13 with connected pawls 16, prevents any reverse movement of the driving gears and motor. All dangers usually encountered in starting an engine are thus obviated and the efficiency and life of the connected parts are considerably increased. 110

The materials and finish of the several parts of the device are such as the experience and judgment of the manufacturer may dictate. 115

Having thus described my invention, what I claim and desire to secure by Letters Patent is—

1. In an engine starting mechanism, the combination of an engine shaft, an electric motor having suitable electrical connections, separable drive connections including a clutch between the motor and the engine 125 shaft, a switch in the motor circuit, a clutch operating mechanism, means whereby on the throwing in of the clutch to couple the motor to the engine shaft said switch is closed, and means acting automatically to detach 130

- said clutch on a reverse movement of the engine shaft.
2. The combination with the crank shaft of an internal combustion engine, of an extension shaft, an electrically driven starting motor, gears connected with said motor to revolve the extension shaft, a jaw clutch connecting the extension shaft with the engine shaft, means for moving said extension shaft longitudinally to throw the jaw clutch into and out of engagement with the engine shaft, means operable by said last-named means for making or breaking a circuit through the starting motor, and means 15 on the extension shaft for automatically throwing the clutch out of engagement if the engine back fires and reverses.
3. The combination with the crank shaft of an internal combustion engine, of an extension shaft, an electrically driven starting motor, gears connected with said motor to revolve the extension shaft, a jaw clutch connecting the extension shaft with the engine shaft, means for moving said extension shaft longitudinally to throw the jaw clutch into and out of engagement with the engine shaft, means operable by said last-named means for making or breaking a circuit through the starting motor, means on the extension shaft for automatically throwing the clutch out of engagement if the engine back fires and reverses, said means comprising a cam clutch, a pair of stud projections secured on the extension shaft engageable with the cam clutch, and means for locking the cam clutch against reverse movement.
4. The combination with the crank shaft of an internal combustion engine, of an extension shaft, an electrically driven starting motor, gears connected with said motor to revolve the extension shaft, a jaw clutch connecting the extension shaft with the engine shaft, means for moving said extension shaft longitudinally to throw the jaw clutch into and out of engagement with the engine shaft, means operable by said last-named means for making or breaking a circuit through the starting motor, means on the extension shaft for automatically throwing the clutch out of engagement if the engine back fires and reverses, said means comprising a cam clutch, a pair of stud projections secured on the extension shaft engageable with the cam clutch, a ratchet wheel secured on the cam clutch, and pawls engageable with the ratchet wheel to lock the ratchet wheel and connected cam clutch against reverse movement, substantially as described and for the purposes set forth.
5. The combination with the crank shaft of an internal combustion engine, of an extension shaft, an electrically driven starting motor, gears connected with said motor to revolve the extension shaft, a jaw clutch connecting the extension shaft with the engine shaft, means for moving said extension shaft longitudinally to throw the jaw clutch into and out of engagement with the engine shaft, means operable by said last-named means for making or breaking a circuit through the starting motor, means on the extension shaft for automatically throwing the clutch out of engagement if the engine back fires and reverses, said means comprising a sleeve surrounding the extension shaft and through which the latter may slide lengthwise, said sleeve carrying a ratchet with means acting on the ratchet to permit the latter to turn in one direction with the engine shaft, and holding the sleeve and ratchet against rotation when the engine shaft turns in the opposite direction, inclined jaws formed on the end of the sleeve and pins secured on the extension shaft which are engageable with the inclined jaws to reciprocate the extension shaft on reverse movement of the engine shaft.
6. The combination with the crank shaft of an internal combustion engine, of an extension shaft, an electrically driven starting motor, gears connected with said motor to revolve the extension shaft, a jaw clutch connecting the extension shaft with the engine shaft, means for moving said extension shaft longitudinally to throw the jaw clutch into and out of engagement with the engine shaft, means for normally holding the said clutch out of engagement, means for making or breaking a circuit through the starting motor, and means on the extension shaft for automatically throwing the clutch out of engagement if the engine back fires and reverses.
7. In an engine starting mechanism, the combination of an engine shaft, an electric motor having suitable electrical connections, separable drive connections including an extension shaft and a clutch between the motor and the engine shaft, a switch in the motor circuit, a clutch operating mechanism, means whereby on the throwing in of the clutch to couple the motor to the engine shaft said switch is closed, and means acting automatically to detach said clutch on a reverse movement of the engine shaft, and means comprising a sleeve surrounding the extension shaft and through which the latter may slide lengthwise, said sleeve carrying a ratchet with means acting on the ratchet to permit the latter to turn in one direction with the engine shaft, and holding the sleeve and ratchet against rotation when the engine shaft turns in the opposite direction, inclined jaws formed on the end of the sleeve and pins secured on the extension shaft which are engageable with the inclined jaws to reciprocate the extension shaft on reverse movement of the engine shaft.
8. The combination with the crank shaft of an internal combustion engine, of an extension shaft, an electrically driven starting motor having an elongated pinion gear secured on its shaft, a spur gear on the extension shaft adapted to intermesh with the elongated pinion, a clutch between the extension shaft and the engine shaft, means for moving said extension shaft longitudinally to throw the jaw clutch into and out of engagement with the engine shaft, means for normally holding the said clutch out of engagement, means for making or breaking a circuit through the starting motor, and means on the extension shaft for automatically throwing the clutch out of engagement if the engine back fires and reverses.

nally to throw the clutch into and out of engagement with the engine shaft, means operable by said last-named means for making or breaking a circuit through the starting motor, and means on the extension shaft independent of the before-mentioned means for moving the extension shaft longitudinally for automatically throwing the clutch out of engagement if the engine back fires and reverses.

9. The combination with the crank shaft of an internal combustion engine, of an extension shaft, an electrically driven starting motor having an elongated pinion gear secured in its shaft, a spur gear on the extension shaft adapted to intermesh with the elongated pinion, a jaw clutch connecting the extension shaft with the engine shaft, means for moving said extension shaft longitudinally to throw the jaw clutch into and out of engagement with the engine shaft, means operable by said last-named means for making or breaking a circuit through the starting motor, means acting normally to disconnect the extension shaft and motor shaft, and means on the extension shaft for automatically throwing the clutch out of engagement if the engine back fires and reverses.

gagement if the engine back fires and reverses.

10. In an engine starter, the combination with the crank shaft of an internal combustion engine, of an extension shaft having a longitudinal movement in line with the engine shaft, clutch connections between the two shafts whereby they may turn in unison in one direction, an electrically-driven starting motor having a motor shaft, an elongated gear on the motor shaft, a companion gear on the extension shaft, said gears remaining in mesh irrespective of whether the extension shaft is coupled to the engine shaft or not, means acting normally to disconnect the extension shaft and motor shaft, means for positively engaging them, and means for preventing reverse movement of the extension shaft if the engine back fires.

In testimony whereof I have hereunto set my hand in the presence of two subscribing witnesses.

GEORGE C. RICHARDS.
